DESIGN FOR A BATHTUB

Warren B. Green, Darien, Conn., assignor to Sears, Roebuck and Co., Chicago, Ill., a corporation of New York

Application October 5, 1945, Serial No. 122,571

Term of patent 14 years

(Cl. D4—4)

To all whom it may concern:

Be it known that I, Warren B. Green, a citizen of the United States and a resident of Darien,
in the county of Fairfield and State of Connecticut, have invented a new, original, and ornamental Design for a Bathtub, of which the following is a specification, reference being had to the accompanying drawing, forming a part thereof.

Fig. 1 is a plan view of a bathtub showing my new design, and

Fig. 2 is a front elevational view thereof.

I claim:

The ornamental design for a bathtub, substantially as shown.

WARREN B. GREEN.
